UNITED STATES PATENT OFFICE.

WATTS COOKE AND DANIEL CARLOUGH, OF PATERSON, NEW JERSEY.

MACHINE FOR UPSETTING EYE-BARS.

SPECIFICATION forming part of Letters Patent No. 380,863, dated April 10, 1888.

Application filed January 14, 1888. Serial No. 260,789. (No model.)

To all whom it may concern:

Be it known that we, WATTS COOKE and DANIEL CARLOUGH, of Paterson, in the county of Passaic and State of New Jersey, 5 have invented a certain new and useful Improvement in Machines for Upsetting Eye-Bars, of which the following is a specification.

The machine is of that class in which a previously-rolled or otherwise manufactured bar of uniform rectangular section throughout and having an excess of length is enlarged at each end, so as to make a suitable strong eye adapted to receive a thick and stout transverse 15 pin, with the metal around the hole as strong as the main body and somewhat stronger.

The operation is effected alternately at each end by heating that end of the bar and, while holding it inclosed in a die of suitable form, 20 strongly compressing it endwise, so as to force more metal into that part and produce the required widening.

Many efforts have been previously made by ourselves and others to effect the upsetting 25 with rapidity and certainty by the aid of machinery. The principles involved in our present machine are similar to those in the machine set forth in the patent to us dated October 12, 1885, No. 328,290. We have invented important improvements in the details.

We provide exchangeable cheeks which extend each side of the eye and shape the whole outline, except the portion which is shaped by direct contact with the end of the heading or upsetting ram. We make these exchangeable cheeks in two pieces on each side, any one of which may be applied and removed independently of the others. The capacity for exchanging serves two purposes. We can, by 35 substituting larger or smaller pieces, adapt the machine for treating different-sized bars and producing different-sized eyes, and we can facilitate the removal of an eye-bar when it has, through the strong pressure given in the 40 upsetting, filled the space very tightly and it requires force to dislodge it. By extending these cheeks along the entire side we better insure the correct shaping of all parts of the eye. We provide round holes in these cheeks and 45 match these holes upon pins in the bed. This

facilitates easy and accurate fitting with ordinary tools. We let the entire lower die move with the metal being upset. We mount this sliding die on anti-friction rollers arranged to afford an efficient support to resist the great 55 strain to which the parts are subjected, while facilitating the ease of movement.

The accompanying drawings form a part of this specification, and represent what we consider the best means of carrying out the invention.

Figure 1 is a side elevation. Fig. 2 is a plan view with certain upper portions removed. Fig. 3 is a longitudinal vertical section on the line *x x* in Fig. 2. Fig. 4 is a central transverse vertical section.

Similar letters of reference indicate corresponding parts in all the figures where they occur.

A is the bed-casting, made with its upper 70 face or the main portion of its upper face grooved transversely to receive a series of anti-friction rollers, W, which roll therein and present their highest points a little above the upper surface of the bed. They carry the 75 lower die, B, and allow it to move endwise with but moderate friction. The bed A is also grooved longitudinally, as shown by *a*, thus providing pockets, which, being cleaned at intervals, tend to avoid difficulty from ham- 80 mer-scales or other dirt which may accumulate. A stout upright projection, B', at the back end of the lower die, B, acts against the end of the hot bar M, to effect the upsetting.

A strong upsetting force is received from a 85 ram, R, actuated by a steam-piston or other device. (Not shown.)

G is the upper die. It is provided with a web, G', of dovetail section, which engages in a corresponding groove in the carrier D, which 90 is raised to allow the removal of the completed eye, and is lowered and held strongly down upon the metal M during the upsetting by the aid of a hydraulic press or other efficient means. (Not represented.)

The holding of the main body of the bar M, which it will be understood is allowed to remain cold to resist the strong upsetting force, may be effected, as is usual in such machines, by an adjustable stop which abuts against the 95 100

outer end of the bar and by a series of clamps which firmly hold down the bar upon the longitudinal beam or support. All this may be of any ordinary or suitable character, but 5 need not be specially represented. The parts which mold and contribute to shape the outline of the eye are fully represented, and will be particularly described.

$A^2 A^2 A^3 A^3$ are cylindrical or slightly-tapering round pins set firmly in the bed A in perpendicular positions. These pins are received in corresponding holes in the exchangeable cheeks and serve to support them against the great strain to which they are subjected.

15 $A' A'$ are stout projections or rests cast or otherwise formed on the bed in the positions represented, which support the cheeks against spreading laterally.

20 $C C$ are the two forward cheeks, which are of the proper form to mold the front of the eye and the neck or the portion by which the eye joins to the body of the bar. It is found that the junction of the eye with the body is peculiarly liable to fracture. We taper these, 25 so as to render the whole of uniform strength or to give a surplus strength here, if desired. The effective ends of these cheeks are supported against spreading by resting squarely against the inner faces of the rests $A' A'$.

30 $K K$ are the back cheeks. The pins $A^3 A^3$, on which they are mounted, resemble in position and function the corresponding pins, $A^2 A^2$, which support the front cheeks, that of resisting the strain and holding the cheeks 35 in position, the arrangement being adapted to allow the cheeks to be easily removed by lifting by hand or by any suitable pry, and to allow them to be easily reapplied even under conditions ill-adapted for nice and acute ob-

40 servation or careful work. These back cheeks differ from the front cheeks in allowing no taper in the channel in which the bar is received. They maintain a space for the bar beyond the eye, which is of uniform section

45 throughout. The ram R acts on the heated metal which lies in this channel and drives it forcibly endwise without much changing its figure. The widening of the hot metal occurs when it emerges from this channel into the

50 liberal space provided for the eye. On thus emerging its width is greatly increased, so as to fill or nearly fill the proper space provided for the eye. The back cheeks, $K K$, are longer than the front cheeks. An extension, K' , on 55 each lies along the inner face of the corresponding rest, A' , and fits obliquely against or close to the adjacent portion of the front cheek.

The construction provides that one front cheek, C, and the corresponding back cheek, K, with its extension K' , may shape the entire side of 60 the eye. The reduction of the thickness of the eye by any suitable means, as by hammering or rolling after its removal from our upsetting-machine, spreads the eye still more, and by a final treatment in a proper box-die 65 completes the perfection of the shape.

Our present invention allows the employment of grooves in the upper and lower dies to form corresponding ridges in the metal to aid in arresting any tendency of the metal to 70 buckle edgewise. We propose to use such if it shall be found expedient; but we believe the machine will succeed perfectly without such grooves in the dies, and consequently without forming any ridges in the eye, which require 75 to be subsequently hammered down or otherwise reduced.

Modifications may be made without departing from the principle or sacrificing the advantages of the invention.

Instead of the rectangular form shown, the cheeks may be shaped to give a circular or elliptical form or egg shape or pear shape to the eye. A greater or less amount of taper of the neck may be produced.

80 Parts of the invention can be used without the whole.

We claim as our invention—

1. In a machine for upsetting eye-bars, in combination with the means for supporting 90 and holding the bar against end movement, the short cheeks $C C$, long cheeks $K K$, supports A, ram R, and means, as the bottom die, B, and top die, G, for restraining the expansion facewise, arranged for joint operation, substantially as herein specified.

2. In a machine for upsetting eye-bars, the series of anti-friction rollers W, mounted in the bed A, in combination with the movable lower die, B, suitable cheeks or edge dies and top 100 die, and the ram R, as herein specified.

In testimony whereof we have hereunto set our hands, at New York city, this 9th day of January, 1888, in the presence of two subscribing witnesses.
